UNITED STATES PATENT OFFICE.

CHARLES SILVER, OF ODENTON, MARYLAND, ASSIGNOR TO PHILIP MILLER, OF ANNAPOLIS, MARYLAND.

TOY VEHICLE.

1,100,031.

Specification of Letters Patent. Patented June 16, 1914.

Application filed July 23, 1913. Serial No. 780,843.

To all whom it may concern:

Be it known that I, CHARLES SILVER, a citizen of the United States of America, residing at Odenton, in the county of Anne Arundel and State of Maryland, have invented certain new and useful Improvements in Toy Vehicles, of which the following is a specification.

This invention relates to improvements in miniature toy vehicles.

The object of my invention consists in providing novel mechanism for moving the toy vehicle operating on a peculiar principle of locomotion, particularly adapted for relatively light bodies. Toy vehicles, as usually designed, are made to have motion when drawn upon as by pulling a string secured to the vehicle, or by some automatic arrangement as by the winding of a spring, but hitherto the novel effect produced upon the wheels of a toy vehicle by agitating a fan has not been fully appreciated. It is a known fact that, usually when an object is subjected to wind pressure it has a tendency to be driven along with the current and not against the current; thus ordinarily a toy vehicle equipped with running gear will be carried along with the current of air set up by the agitation of wind induced by a fan,— in other words the object would be repelled and not attracted by the wind. Contrary to this natural tendency of repulsion I have devised a toy arrangement governed by the principle of attracting the toy vehicle, making it move against the wind current toward and in the direction of the primary mover or source of wind agitation. The effect produced upon the mind of the observer of this toy vehicle when it is set in motion as above described is both delusory and instructive and makes it an especially fit object of demonstration when embodied in a toy.

With the above and other objects in view my invention consists in the arrangement, combination, and details of construction disclosed in the drawings and specification, and then more particularly pointed out in the appended claims.

Referring to the drawings wherein similar reference characters relate to similar parts throughout the perspective views, Figure 1 is a perspective view of my invention, Fig. 2 is a side elevation thereof, partly in section, Fig. 3 is a cross-sectional elevation thereof, Fig. 4 is a side elevation, partly in

section of a modification of my invention, Fig. 5 is a top plan view of said modification with the vehicle body removed, and Fig. 6 is an end elevation, partly in section, of said modification.

Referring to the drawings by numerals there is shown at 1 a suitably shaped body which, by way of illustration is shown box-like in contour, although any other shape may be given the vehicle body. Formed at the bottom of the vehicle body 1 is an opening 2 into which may project the grooved wheel or disk 3, or a belt or band 4 which is trained over this disk and which disk is arranged substantially at right angles with respect to the grooved wheel or disk 5 fixed upon the shaft 6, said belt 4 being also trained over the disk 5. Shaft 6 extends longitudinally from end to end of the vehicle-body 1 and may pass through the bushings 7 carried by said vehicle body, although this is optional.

8 designates oppositely-arranged brackets or supports dependently mounted upon the vehicle body 1, which brackets serve as a bearing for the transversely-extending shaft 9, upon the opposite ends of which are fixed the pinions 10 projecting within the plane of the wheels 14 so as to mesh with the circular racks 11 preferably embedded within said disks. The wheels 14 are formed with flanges 12 upon which are concentrically secured the circular racks 11, suitable hubs 13 being formed upon the forward traction wheels 14, a suitable axle 15 connecting said wheels 14 and being mounted on said brackets 8. The hind or driven wheels are designated 16, being mounted upon the axle 21 secured in the oppositely-arranged brackets or supports 22 dependently mounted upon the vehicle-body 1. Formed upon the shaft 6 at one end which projects beyond the vehicle body 1 is a poly-sided part 17 upon which is fixed a propeller 18 of any desirable construction. A propeller fan peculiarly adapted for use in connection with the toy vehicle because of the shape of its blades and ease of construction is shown and described in a divisional application filed by me. The traction wheels 14 may be held against displacement from the axle 15 by any suitable means such as the cotter pins 19.

20 designates a suitable wind generating or agitating member such as a fan designed

to exert wind pressure as a primary mover for causing propeller 18 to rotate which in turn is adapted to move the vehicle.

It is particularly to be noticed that the 5 grooved disk 3 is materially larger than the wheel or disk 5 and that the pinions bear a defined proportional size relatively to the diameter of the traction wheels 14. I do not limit myself to the particular gearing or 10 transmission mechanism herein set forth as a means for rotating the traction wheels when the propeller shaft 6 is rotated. The fan 20 will be caused to stir or agitate the air so as to set up an induced current of 15 air effective to rotate the propeller 18, as shown in Fig. 1, and as said propeller revolves the grooved disk 5 will rotate and through the medium of the belt 4 will rotate the grooved disk 3 whereupon shaft or 20 axle 9 will turn around causing the pinions 10, meshing with the circular racks 11 to rotate the traction wheels 14, which wheels will rotate in such a direction that the vehicle-body 1 will move against the air current, —i. e.—instead of the body being 25 pushed or impelled in advance of the current it will move in an opposing direction or against the current, as long as the current exists exerting a sufficient pressure to cause 30 the propeller 18 to rotate continuously and uninterruptedly. The varying sizes of the gear wheels is an important factor in the operation of my invention as it obviates much friction. The currents of air are 35 converted into such a source of mechanical power as will make the energy given out be exerted in rotating the propeller instead of impinging against the sides of the vehicle-body. The propeller should be relatively of 40 a large size compared with the height of the vehicle body and should preferably project above the plane of the latter so as to remove the tendency of part of the air acting on the body of the vehicle.

45 In Figs. 4, 5, and 6 there is illustrated a modification of my invention characterized by greater simplicity of construction than the type of toy vehicle already described. Referring to said figures it will be seen that 50 a substantially torpedo-shaped hollow body 33 is illustrated, being so shaped to encounter but very little wind resistance when it is impelled forward. A shaft 32 extends longitudinally within said torpedo-shaped body 33 and projects beyond one end thereof. At the rear end of the shaft 32 is fixed a 55 relatively small grooved-wheel 23 over which is trained the belt or band 24 which is also wound around a deep-seated groove 60 formed upon the single hind traction wheel 26, said groove being formed in such a way that the band will not touch the surface over which the toy vehicle is moved. A 65 suitable frame shown by way of illustration, in the form of a U-shaped tree 27 is pro-

vided, said tree being formed with upturned ends 28 upon which is suitably mounted a relatively wheel 26. The opposing arms of said tree 27 support the axle 29 upon the ends of which are revolvably mounted a pair of traction wheels 30. The torpedo-shaped body 33 is suitably supported by means of the upright posts or members 31, four being shown in number, although a different number may be employed should it be desired. 75 The propeller 18 is secured upon the projecting end of the shaft 32 and when it is revolved by the agitation of air as already described the shaft 32 will be revolved, and so will the small grooved wheel 23, thereby 80 setting the belt 24 in motion and rotating the rear traction wheel 26, whereupon the torpedo-shaped body will be driven forwardly in a direction counter to the current generated by the fan, etc., this modification 85 illustrates that it is possible to dispense with certain elements of gearing so as to produce a relatively light and compact vehicle body capable of moving at good speed at the expenditure of little exertion.

It is obvious that numerous other modifications may be resorted to in practice without departing in principle from the details of construction herein set forth. I do not therefore, limit myself to the exact particulars of construction save as pointed out in the appended claims.

What I desire to claim and seek protection for is:—

1. A device of the kind described comprising a vehicle body, wheels carried by said vehicle-body, axles upon which said wheels are mounted, a shaft carried by said vehicle body at right angles to said axles, a propeller mounted on said shaft, and means controlled by said propeller, when in motion, for imparting motion to said wheels.

2. A device of the kind described comprising a shaft, a propeller mounted on said shaft, means for supporting said shaft, wheels carried by said support arranged at right angles with respect to said propeller, said propeller adapted to be rotated by air agitation, and means actuated by said propeller for rotating said wheels.

3. In combination a miniature wagon, wheels carried by said wagon, a propeller carried by said wagon and arranged to be set in motion by a primary mover, and means controlled by said propeller for causing said wheels to rotate and said wagon to move only in the direction of the primary mover.

4. In a miniature toy wagon the combination of a vehicle body, wheels mounted upon said vehicle body, a propeller mounted parallel with one of the end walls of said vehicle body, and gearing connecting said propeller and said wheels whereby the wheels revolve as said propeller revolves.

5. In combination a miniature wheeled

structure, a propeller carried by said wheeled structure, said propeller being wind actuated, and means actuated by said propeller arranged to move said wheeled structure forwardly said propeller being arranged at right angles to the axis of said wheeled structure.

6. In combination a vehicle body, wheels carried by said vehicle body, a propeller disposed transversely of said vehicle body, and arranged to be wind actuated, and means controlled by said propeller as it revolves for revolving said wheels.

7. A device of the kind described comprising a vehicle body, traction wheels carried by said vehicle body, a propeller mounted transversely of said vehicle body and having blades arranged to be actuated from either side of said propeller, and means actuated by said propeller for causing said wheels to move toward the direction of the wind current.

8. In combination, a miniature vehicle body, traction wheels carried by said vehicle body, a propeller arranged to be wind actuated, and means whereby said propeller as it rotates is designed to move said traction wheels forwardly.

9. A toy comprising a vehicle body, trac-

tion wheels upon which said vehicle body is mounted, a shaft disposed longitudinally on said vehicle body, and projecting forwardly thereof, a propeller mounted at the free end of said shaft and projecting above the vehicle body, gear wheels for rotating said traction wheels, and means controlled by said propeller for actuating said gear wheels.

10. A toy comprising a frame, traction wheels mounted on said frame, a shaft mounted longitudinally within said frame and projecting therefrom; a propeller wheel mounted upon the projecting end of said shaft, a grooved wheel mounted upon said shaft, a shaft disposed at right angles to said first-named shaft, a grooved wheel on said second shaft larger than said first-named grooved wheel, a band trained over said grooved wheels, oppositely-arranged pinions formed upon said first-named shaft, and circular racks carried by said forward traction wheels meshing with said pinions.

In testimony whereof I affix my signature in presence of two witnesses.
